UNITED STATES PATENT OFFICE.

CHESTER M. PALMER, OF AURORA, ILLINOIS.

SHEARING-MACHINE.

No. 877,517.

Specification of Letters Patent.

Patented Jan. 28, 1908.

Application filed September 4, 1908. Serial No. 333,120.

To all whom it may concern:

Be it known that I, CHESTER M. PALMER, a citizen of the United States, of Aurora, in the county of Kane and State of Illinois, have invented certain new and useful Improvements in Shearing-Machines; and I do hereby declare that the following is a full, clear, and exact description thereof, reference being had to the accompanying drawings, and to the letters of reference marked thereon, which form a part of this specification.

This invention relates to improvements in shearing machines for shearing or clipping the wool of animals, and the invention consists in the matters hereinafter set forth and more particularly pointed out in the appended claims.

Among the objects of the invention is to improve the pivotal connection of the vibratory cutter lever with the frame; to improve the tension device by which proper tension of the cutting knife is maintained on the guard-fingers or comb of the frame; to provide an improved connection between the cutter and the vibratory cutter lever, and to provide an improved construction of the part of the casing which affords bearing for the driving shaft of the machine. Other objects of the invention will appear from the foregoing description.

In the drawings: Figure 1 is a plan view of a shearing machine made in accordance with my invention. Fig. 2 is a longitudinal, vertical section thereof. Fig. 3 is a section, taken on line 3—3 of Fig. 2, looking forwardly. Fig. 4 is a section, taken on line 4—4 of Fig. 2, looking rearwardly. Fig. 5 is a section, taken on line 5—5 of Fig. 4, looking downwardly. Fig. 6 is a perspective view of the post constituting the pivot for the vibratory cutter lever. Fig. 7 is a longitudinal view, similar to Fig. 2 showing a modified form of the vibratory cutter lever. As shown in the drawings, A designates, as a whole, the casing which constitutes the frame of the machine, comprising a top wall a, a bottom wall a' and side walls a''. Rigidly connected with the casing is a tubular extension B consisting of a tube having screw-threaded connection at its front end with the rear end of the casing. Said tube B affords bearing for the driving shaft C of the machine. The driving shaft is provided at its rear end with a gear c which meshes with a gear d of a shaft D that is adapted for connection with a flexible shaft, not shown, and

through the medium of which power to operate the cutter is transmitted to the machine. The said shaft D is mounted in a tubular casing D' that has a hollow or bell-shaped end d' inclosing the gear d and is suitably connected with a like bell-shaped part b of a sleeve b' that is slipped over the rear end of the bearing tube B. The bearing tube B constitutes the handle of the machine, and is, in practice, covered with a suitable leather cover, which overlaps the rear end of the frame A and the front end of the tubular casing D.

E designates the vibratory cutter lever or fork which carries at its front end the cutter E', and is mounted on a pivot post F, which latter is disposed transversely to the axis of the shaft C, and is rotatively mounted so as to have rocking motion in upper and lower bushings a' a'' having screw-threaded connections with the upper and lower walls, a a'', respectively, of the frame A. The cutter carried by the forward end of the lever, is provided with teeth e and has vibratory engagement with the teeth of a comb or guard-plate G, which latter is attached to the bottom wall of the casing A, as by means of screws g. Said cutter lever E is provided at its rear end with a vertical socket E'' in which operates a ball-bearing crank c' extending forwardly and eccentrically from the forward end of the driving shaft C, whereby vibratory motion is given to the said cutter lever and the cutter carried thereby, through the rotary action of said shaft. In accordance with one feature of my invention, the said cutter E' is not carried directly by the cutter lever, but an intermediate plate H, attached to the lever by means of a screw h, is interposed between said lever and cutter. As herein shown, the lateral members or arms e' e'' of the vibratory cutter lever are apertured and screws or studs e' e'' extend downwardly through said apertures and have screw-threaded engagement with said arms and extend also through apertures in the intermediate spring or resilient plate H, as shown in Fig. 3. The said screws e' are provided with downwardly facing conical shoulders e' e'' (Fig. 3) which oppose upwardly facing conical shoulders surrounding the apertures of the intermediate or spring plate, and the lower ends of said screws are cylindric and engage said openings in the cutter. The parts are preferably so arranged

that the arms of the cutter lever do not bear directly on the spring or intermediate plate. The said intermediate spring-plate H is provided with forwardly extending lugs 5 or arms h², there being a number of such arms equal to the number of teeth e of the cutter, one arm bearing on each tooth. This arrangement insures a uniform bearing of the cutter on the guard-plate, notwithstanding inaccuracies of fit due to wear or other cause; the resilient action of the intermediate spring-plate insuring that the said arms of the plate will act with uniformity to evenly press the cutter on the guard-plate or comb. Furthermore, the flexible or loose connection of the intermediate plate with the cutter lever through the screws e², which also constitute the connection of the cutter with said cutter lever, permits the arms of the lever to have a slight pivotal action on the plate, which co-operates with the resiliency of the plate to apply the tension device pressure on the cutter in a manner to insure uniform cutting action of the teeth on the guard-plate.

Another function of the interposed resilient plate H between the cutter and vibratory cutter lever is that, with the same vibratory cutter lever, resilient or spring-plates of different dimensions may be used in connection with different sized cutters. For instance, a plate designed to be used in connection with a cutter having but three teeth may be employed with the same advantageous effect, and this effect is produced with only the replacement of the spring-plates and without the necessity of replacing the cutter lever itself. If a cutter having three teeth be employed, the spring-plate H interposed between the cutter lever and the cutter will be provided with but three bearing lugs or arms h² which engage the blades of said cutter. A further advantage of this arrangement is that, the pressure exerted on said vibratory cutter lever to hold the cutter on the comb or teeth does not tend to break said lever and should such pressure tend to injure the projections h² of the resilient plate, which bear directly on the teeth of the cutter, the plate H only need to be replaced. The tension exerted on said cutter lever to maintain the cutter in proper relation to the teeth of the comb or guard plate is effected through the pivot post F and the construction and arrangement of the parts are such that the post, which carries the vibratory cutter lever is maintained at all times at the same angle to the cutter lever and all the tension applied thereto is exerted on the front end of the lever to hold the cutter against the guard-plate or comb, while the rear end of the lever is free from engagement with a friction surface. The construction of the parts, however, is such that the cutter lever is free to rock slightly on its longitudinal axis to permit it to properly adjust

itself and the cutter carried thereby to maintain a uniform contact of the cutter with the guard-plate. The construction of said pivot post and its relation to the vibratory cutter lever and tension device will now be described. The said pivot post F, which is shown in Fig. 6 as detached from the casing, comprises upper and lower cylindric portions f f¹ which have rotative bearing, respectively, with the bushings a³ a⁴ before referred to and extends through a vertical opening in said cutter lever. The post is provided mediate its ends with a downwardly facing spherical shoulder f² which engages and bears downwardly on an upwardly facing complementary socket e⁵ in the vertical aperture of the cutter-lever E, as more clearly shown in Figs. 2 and 4. The post is also provided with one or more flat bearing surfaces f³, herein shown as formed on a flange f⁴. The said flat surface of the post is designed to engage an opposing flat surface e⁶ on the upper face of the lever, as herein shown, for a purpose hereinafter to be described.

I designates a tension screw that extends into and has screw-threaded engagement with the upper bushing a³ and bears at its lower end on the upper end of the cylindric portion f of the pivot post. Said tension screw is provided with a knurled head i and the under face of the head is provided with a plurality of lugs i¹ between which are formed notches that are adapted to be engaged by the end of a locking spring J attached to the frame of the machine. The tension screw operates through its engagement with the upper end of the pivot-post, together with the engagement of the spherical portion f² of the post with the complementary socket e⁵ in the cutter lever and the engagement of the flattened surface f³ of the post with the flattened surface or shoulder e⁶ on the cutter lever, to press the cutter lever and the cutter downwardly. By reason of the engagement of the post at two separated points with the lever, to wit,—the engagement of the spherical shoulder f² with the spherical socket of the lever and the engagement of the flattened surface f³ with the opposing surface e⁶ on the lever, the lever as it is pressed downwardly by the tension screw I maintains a fixed angle to the post, and the tension screw acts, through the lever, to press the cutter on the guard-finger, but does not press the rear end of the lever against an opposing part of the bottom wall of the casing. While the cutter lever, when thus pressed downwardly by the tension screw, maintains a fixed angle to the post for the reason set forth, yet the spherical engagement of the post and lever permits a slight rocking movement of the lever on its longitudinal axis to permit the cutter carried by the lever to properly adjust itself to the guard-plate or comb, and such slight rocking movement of the lever is not effected by an-

gagement of the flattened shoulders f^3 e^4 on the post and lever, respectively, because said surfaces are free to slip or oscillate one upon the other. The same results will be secured

- 5 if the relative positions of said spherical and flattened shoulders of the post be reversed and their contacting surfaces or shoulders on the lever be likewise reversed. A plurality of flattened portions f^3 may be provided on the post to enable the post, which has only a limited rotative movement in each reciprocation of the cutter lever to be partially turned as it becomes worn to present new bearing surfaces of the parts f f^1 to the bushings a^3 a^4 , thereby lengthening the effective life of the post.

The provision of the upper and lower bushings a^3 a^4 of the casing possesses the important advantage that when said bearings 20 are worn so as to affect the alinement of the post, this defect may be readily remedied by merely replacing the bushings, thereby avoiding the necessity of replacing the more expensive casing or frame A, which would 25 occur in the event that the post had direct rotative engagement with the apertures in the upper and lower walls of the said frame.

The arrangement whereby the sleeve B, in which the driving shaft C has bearing, is 30 made separate from the casing A and has suitable detachable connection therewith, is advantageous inasmuch as it provides an exceedingly simple and durable bearing and one which enables one of the parts to be 35 readily and economically replaced in case of wear, or injury of the other part. The said shaft is reduced, as indicated at b^2 , to provide an oil chamber within the bearing sleeve or casing B, and said casing B is provided with 40 an oil opening that is closed by a suitable screw b^3 (Fig. 2).

In Fig. 7 I have shown a modification of the tension device and the vibratory cutter lever, wherein the spherical shoulder f^2 shown in the other figures is replaced by a flange f^3 which engages a recess in the upper face of said vibratory cutter lever. In order to afford the even or uniform adjustment of the forward end of the vibratory cutter lever 45 on the cutter, I make such lever in two parts connected by a screw e^6 thereby permitting the forward end of said lever to have a slight rocking movement to adjust itself, relative to the rear end of the lever arm as occasioned by the demands or requirements of the fit of the forward part of said lever and its interposing spring-plate H upon the cutter. In other respects, the machine shown 50 in Fig. 7 is like that shown in the other figures and like parts are designated by the same reference letters.

A spring K herein shown as a spiral spring and surrounding the post F, is interposed between the cutter lever and the bottom wall 55 of the casing for the purpose of pressing the

lever away from the bottom wall of the casing and automatically releasing the cutter when the tension device is released.

I claim as my invention:—

1. In a shearing machine, the combination 70 with a casing, a guard-plate and a cutter movable on said guard-plate, of a vibratory cutter lever, a pivot post having rotative bearing in the upper and lower walls of said casing and non-rotatively engaging between its ends said lever, means for applying tension to said lever through said post, means whereby the lever and the cutter carried thereby may have a slight rocking movement with respect to the post to permit uniform pressure of the cutter on the guard-plate, and means whereby a fixed angle between the post and lever is maintained, including a flat bearing surface on the post 75 which has sliding bearing with the lever. 80

2. In a shearing machine, the combination 85 with a casing, a guard-plate and a cutter movable on the guard-plate, of a vibratory lever for operating the cutter, a post extending through an aperture in said lever and having rotative bearing in the upper and lower walls of the casing, means for vibrating said lever, a tension device acting through the post on the vibratory lever for pressing the cutter against the guard-plate, means 90 for effecting even pressure of the cutter on the guard-plate, and means for maintaining the post at a fixed angle to said lever, including a flat surface on the post engaging a complementary surface on the lever. 95

3. In a shearing machine, the combination 100 with a casing, a guard-plate and a cutter movable on the guard-plate, of a vibratory cutter lever, a pivot post having rotative bearing at its ends in the casing and engaging between its ends said lever, and means for applying tension to said lever through said post, said post having an oscillating and sliding engagement with the lever at vertically separated points, for the purpose set forth. 110

4. In a shearing machine, the combination 115 with a casing, a guard-plate, and a cutter movable on the guard-plate, of a vibratory lever carrying at its front end said cutter and free from bearing contact at its rear end with the casing, a pivot post having bearing in the upper and lower walls of the casing and engaging between its ends said lever, means for applying tension to the lever 120 through said post, and means whereby a fixed angle between the post and the lever is maintained including a flat surface on the post engaging a complementary surface on the lever. 125

5. In a shearing machine, the combination 130 with a casing, a guard-plate, and a cutter movable on the guard-plate, of a vibratory lever operating said cutter, a post extending through an aperture intermediate

the ends of the lever, and having bearing in the upper and lower walls of the casing, and a tension device acting through said post to press the cutter on said guard-plate, said post being provided with two vertically separated bearing surfaces or shoulders, one made flat and facing forwardly, and the other spherical and facing downwardly adapted to engage complementary bearing surfaces on said lever.

6. In a shearing machine, the combination with a casing, a guard-plate, and a cutter movable on the guard-plate, of a vibratory lever operating said cutter, a post extending through an aperture intermediate the ends of the lever, and having bearing in the upper and lower walls of the casing, a tension device acting through said post to press the cutter on said guard-plate, said post having a downwardly facing spherical bearing surface engaging a complementary bearing surface in said lever and provided with a flattened, forwardly facing surface designed to engage a like flattened surface on the lever between said post and cutter.

7. As a new article of manufacture, a pivot post for the vibratory cutter lever of a shearing machine, comprising upper and lower cylindric bearing portions, a downwardly facing spherical bearing, and a laterally facing shoulder or flattened surface on the post vertically separated from the spherical bearing surface.

8. As a new article of manufacture, a pivot post for the vibratory cutter lever of a shearing machine, comprising upper and lower cylindric bearing portions, a downwardly facing spherical bearing surface, and a flange vertically separated from said spherical surface provided with a flattened surface, for the purpose set forth.

9. In a shearing machine, the combination with a casing, a guard-plate, and a cutter movable on the guard-plate, of a vibratory lever for operating the cutter, a post extending through an aperture in and non-rotatively engaging said lever and having rotative bearing in the upper and lower walls of the casing, means for vibrating said lever, a tension device acting through the post on the vibratory lever for pressing the cutter against the guard-plate, and a spring

surrounding the post and interposed between the vibratory lever and lower wall of the casing for the purpose set forth.

10. In a shearing machine, the combination with a casing, a guard-plate and a cutter movable on said guard-plate, of a vibratory lever for operating said cutter, a tension device acting through said lever to press the cutter on the guard-plate, a spring device interposed between said cutter and the forward end of the vibratory lever, and screws or studs extending downwardly from the lever and provided with downwardly facing shoulders opposing upwardly facing shoulders on the spring device and provided also with extensions adapted to engage registering openings in the cutter.

11. In a shearing machine, the combination with a casing, a guard-plate and a cutter movable on said guard-plate, of a vibratory lever for operating said cutter and capable of a rocking movement, a tension device acting through said lever to press the cutter on the guard-plate, a spring device interposed between said cutter and the forward end of the vibratory lever, and screws or studs extending downwardly from the lever and provided with downwardly facing rounded shoulders opposing like upwardly facing shoulders on the spring device and provided also with extensions adapted to engage registering openings in the cutter, said lever and plate being spaced apart for the purpose set forth.

12. In a shearing machine, the combination with the vibratory cutter lever and its cutter, of a spring device interposed between the cutter and lever, screws or studs extending downwardly from the lever and engaging openings in the spring device, said screws or studs having downwardly facing rounded shoulders engaging complementary shoulders on the spring device.

In testimony, that I claim the foregoing as my invention I affix my signature in the presence of two witnesses, this 25th day of August A. D. 1906.

CHESTER M. PALMER.
